PUSH BUTTON SWITCH UNIT FOR TURN SIGNAL INDICATORS

William L. Mappes, Cincinnati, Ohio, assignor to Northeast Capital Corporation, New York, N.Y., a corporation of New York

Application February 18, 1959, Serial No. 54,672

Term of patent 14 years

(Cl. D26—13)

Fig. 1

Fig. 2

Fig. 3

Figure 1 is a perspective view of a push button switch unit for turn signal indicators embodying my ornamental design.

Figure 2 is a top plan view of the switch unit in Figure 1.

Figure 3 is a front elevational view of the switch unit of Figure 1.

The rear face of the switch (not shown) appears substantially the same as the front face except that it is substantially planar and has no buttons protruding therefrom.

I claim:

The ornamental design for a push button switch unit for turn signal indicators, substantially as shown and described.
